[57] CLAIM

The ornamental design for a intramedullary brush, as shown and described.

DESCRIPTION

FIG. 1 is a side elevational view partially broken away of an intramedullary brush showing my new design;
FIG. 2 is an enlarged left end elevational view thereof;
and
FIG. 3 is an enlarged right end elevational view thereof.
The brush is intended to uniformly continue throughout the broken line area.

Fig. 1.
